UNITED STATES PATENT OFFICE.

EDWIN M. ROSENBLUTH, OF PHILADELPHIA, PENNSYLVANIA.

DESIGN FOR A BURNER DRAFT-DOME.

SPECIFICATION forming part of Design No. 33,698, dated December 11, 1900.

Application filed October 24, 1900. Serial No. 34,214. Term of patent 14 years.

To all whom it may concern:

Be it known that I, EDWIN M. ROSENBLUTH, of Philadelphia, in the State of Pennsylvania, have invented and produced a new and original Design for Burner Draft-Domes, whereof the following is a specification, reference being had to the accompanying drawings.

In the accompanying drawings, Figure 1 is a perspective view of a burner draft-dome embodying the essential features of my design. Fig. 2 is a vertical sectional view of the draft-dome shown in Fig. 1.

In said figures, A is the draft-dome, which is of larger diameter at its bottom B than at its top C and of bell shape or conoidal contour. Said top C is truncated and provided with a concentric opening c, and the side of said dome is provided with an eccentric open-

ing D, comprising a vertical slot d, which merges at its lower extremity into a horizontal slot d'.

The material feature of my design is the conoidal or bell-shaped shell A, provided with a concentric opening c in its truncated top C and an eccentric opening D in its side, the latter opening being of greater circumferential extent at its bottom than at its top.

Having described my invention, what I claim as new, and desire to secure by Letters Patent, is—

The design for a burner draft-dome as herein shown and described.

EDWIN M. ROSENBLUTH.
